UNITED STATES PATENT OFFICE.

GEORGES PIGNAL, OF TUBIZE, BELGIUM, ASSIGNOR TO FABRIQUE DE SOIE ARTIFICIELLE DE TUBIZE, SOCIETE ANONYME, OF BRUSSELS, BELGIUM.

DRAWING-FRAME CARRIER FOR THE SPINNING OF ARTIFICIAL TEXTILE MATERIALS.

Application filed July 22, 1924. Serial No. 727,407.

To all whom it may concern:

Be it known that I, GEORGES PIGNAL, a citizen of the French Republic, residing at Tubize, in the Kingdom of Belgium, have 5 invented certain new and useful Improvements in Drawing-Frame Carriers for the Spinning of Artificial Textile Materials, of which the following is a specification.

My invention relates to a drawing frame 10 carrier for the spinning of artificial textile materials. In most of the devices of this kind used hitherto, use is made, as is known, of a rectilinear metal gutter pierced with a row of holes through which is forced the liquid which is to produce the filaments to 15 be manufactured; this gutter or metal drawing-frame cooperates generally with a filtering device removing from the spinning liquid the impurities contained therein before it passes through the holes of the drawing frame.

In these known constructions the filtering surface corresponds with the upper section 20 of the gutter; the result of this is that this filtering surface is clogged in a comparatively short time, long before the spinning orifices are stopped up or clogged by the impurities which may have escaped the action of the filtering surface.

25 The replacing of the filtering surface then requires a dismounting of the drawing-frame and consequently an interruption of the work and considerable manual labour, also in most cases these operations are hindered by the difficulties arising from the dismounting of the drawing-frame with a view to obtaining access to the filtering surface.

30 My invention has for its object to obviate these inconveniences. With this object in view it essentially consists in the special arrangement and combinations of parts as hereinafter fully described and pointed out in the appended claims.

35 The accompanying drawing shows by way of example a drawing-frame constructed according to my invention.

Fig. 1 gives a view in front elevation of 40 the whole of the drawing-frame in its position of use.

Fig. 2 gives a longitudinal section of the same drawing-frame.

Fig. 3 is a view in end elevation of the 45 whole of the drawing-frame at work.

Fig. 4 is a cross section taken through the 55 line 4—4 in Fig. 2.

According to my invention in order to decrease the frequency of the dismountings of the drawing-frame the latter is provided with a filtering surface large enough for 60 the duration of clogging of the cloths to be at least equal to that of the gutter, so that the replacing of the filtering cloths only becomes necessary when the replacing of the gutter should also be effected.

65 In the practical construction of the invention, the filtering cloths of large surface are independent of the gutter properly so-called which can eventually cooperate as usual with an auxiliary filtering surface, further the filtering cloths of large surface are mounted in a chamber of large capacity closed between two parts of the drawing-frame which are independent of the part serving to secure the gutter properly so 70 called. For this purpose the drawing-frame is preferably composed of three parts on a rectangular bowl-shaped base serving as support to the gutter in order to prevent any distortion thereof under the action of 75 the pressure, an intermediate member being applied on the base member and provided with a feed passage for the spinning liquid and a third member forming a lid provided with a joint at the delivery. Between the 80 intermediate member and the member forming a lid is provided a chamber of large capacity in which is placed the principal filtering surface, the whole of the three parts composing the drawing-frame 85 are assembled with the aid of two braces provided with pressure screws exerting a vertical pressure on the members secured in the braces.

90 As shown by the figures the drawing frame includes a rectangular base *a* in the shape of bowls having along its long axis a groove for holding the gutter *a'*, this base is provided on its long sides with four 95 dowels *b* on which are jointed tightening braces *c*.

100 The metal gutter *a'* pierced with holes *a''* is placed after interposition of a joint, on the bottom of the bowl. It is covered with 105 a filtering fabric *d* which is joined round the drawing-frame under the pressure of the base of a member *e* provided with a rectangular passage *f* which expands at the

- top in the shape of a bowl *g* (Fig. 4) in which is placed a grating *h* which sustains a filtering fabric *i* of a surface about thrice the surface of the filtering fabric *d*.
- 5 This fabric *i* forms at the same time junction between the member *e* and a lid *j* which carries at its centre a shoulder-piece *k* pierced and screw-threaded so as to be screwed on the support and feed tube *m*. On each 10 side of the shoulder piece *k* the lid *j* has two small bore-holes *n* which receive the tips of screws *l* passing through the braces *c* and ensuring the compression and air tightness of the whole when the braces are in 15 the position shown by the drawing.

The edges of the shoulder-piece *k* form in this case a stop-bearing for the braces.

- Owing to the construction described the 20 dismounting and remounting operations are summed up in the following actions:

For the dismounting, one unscrews the two screws *l* and turns back sideways the braces by rotating them on the dowels *b*; one then removes successively the members 25 *j* and *e* which only rest one on the other. For the remounting one places successively the different members upon the base and one above another, one first puts into place the gutter *a'*, then the filtering cloth *d*, then 30 the intermediate member *e*, after that the grating *g* the filtering cloths *i* and finally the lid *j*; one then turns up again the braces *c* and one locks the whole by means of the screws *b*. During this remounting operation 35 there is no fear of any disturbance of the members composing the drawing-frame and more especially of the filtering cloths *d* and *i* these cloths being secured by the simple superposition of the members without any longitudinal or lateral displacement of said frame. On the other hand, owing 40 to the large surface of the filtering cloths *i*, the duration of action of these cloths is considerably longer than previously or than 45 if only the filtering cloth *d* were used co-operating immediately with the gutter *a'*.

In these conditions the drawing-frame can work without needing dismounting up to the point where the holes *a²* of the gutter 50 itself end by being clogged, which necessitates the replacement of the gutter.

The dismounting is therefore to some extent limited to the sole case in which the 55 replacing of the gutter forming a drawing frame has become necessary. Hence results a great saving of manual labour to which are added the advantages resulting from the great facility with which the dismounting and remounting are effected.

60 What I claim is:

1. In a device of the kind described in combination with a base having a longitudinal groove, a gutter, the said gutter being

provided with holes, a filtering surface the 65 said surface having a section considerably larger than the maximum section of the gutter and means for holding the filtering surface above the gutter.

2. In a device of the kind described, a base having a longitudinal groove, a gutter 70 placed in the said groove, the said gutter being provided with holes, a chamber above the gutter, the said chamber having a widened section relatively to the gutter, a filtering surface arranged in the said chamber of 75 large section and means for holding the filtering surface in the said chamber.

3. In a device of the kind described a base having a longitudinal groove, a gutter placed in the said groove, the said gutter 80 being provided with holes, an auxiliary filtering surface arranged on the upper part of the gutter, a chamber above the said auxiliary filtering surface, the said chamber having a widened section relatively to the 85 gutter, a principal filtering surface arranged in the said chamber and means for holding the said filtering surface in the said chamber.

4. In a device of the kind described, a 90 base having a longitudinal groove, a gutter placed in the said groove, the said gutter being provided with holes, an auxiliary filtering surface arranged on the upper part of the gutter, a separate member placed on 95 the base, whereby the gutter and the auxiliary filtering surface are kept in place in the base, the said member forming a chamber having a widened section relatively to the gutter, a principal filtering surface arranged in the said chamber, a lid placed on the said member and means whereby the base, the member and the lid are pressed one on the other.

5. In a device of the kind described a 105 base member provided with an axial groove, a gutter placed in the said groove the said gutter forming a drawing-frame, an intermediate member applied on the base and securing on the latter a first filtering cloth, 110 this intermediate member being provided with a rectangular passage expanding at the top in the form of a bowl, a grating placed in this bowl and supporting a principal filtering surface, and an upper member forming a lid and bearing on the intermediate member, the intermediate member and the lid being pressed one on the other and on the base member by means of two 115 braces pivoted on dowels integral with the base member and provided with pressure screws acting on the member forming a lid.

In testimony whereof I have affixed my signature.

GEORGES PIGNAL.
